DESIGN FOR A FLUORESCENT LAMP FIXTURE

Jacob Kurtz, Teaneck, and Joseph Spina, Cliffside Park, N. J., assignors to Callite Tungsten Corporation, Union City, N. J., a corporation of Delaware

Application January 2, 1941, Serial No. 97,784

Term of patent 14 years

To all whom it may concern:

Be it known that we, Jacob Kurtz and Joseph Spina, citizens of the United States, residing at 736 Grange Road, Teaneck, New Jersey, and 72 Washington Avenue, Cliffside Park, New Jersey, respectively, in the county of Bergen and State of New Jersey, have invented a new, original, and ornamental Design for a Fluorescent Lamp Fixture, of which the following is the specification, reference being had to the accompanying drawing, forming part thereof.

Fig. 1 is a side perspective view of the fluorescent lamp fixture, showing our new design; and Fig. 2 is a top perspective view of the same.

The broken lines appearing at the ends of the supports are employed to indicate indeterminate length.

We claim:

The ornamental design for a fluorescent lamp fixture, as shown and described.

JACOB KURTZ.
JOSEPH SPINA.
